UNITED STATES PATENT OFFICE.

MOSES D. WELLS, OF MORGANTOWN, VIRGINIA.

IMPROVEMENT IN SEEDING-MACHINES.

Specification forming part of Letters Patent No. **23,630**, dated April 12, 1859.

To all whom it may concern:

Be it known that I, MOSES D. WELLS, of Morgantown, in the county of Monongalia and State of Virginia, have invented a new and useful Improvement in Seeding-Machines; and I do hereby declare that the following is a full, clear, and exact description of the same, reference being had to the annexed drawings, forming part of this specification, in the several figures of which similar characters of reference denote the same part.

Figure 1 is a top view of the seeder. Fig. 2 is a vertical section on $x x$. Fig. 3 is a vertical section on $y y$.

This invention consists in a certain combination of devices pertaining to the discharge mechanism, hereinafter to be set forth.

In the drawings, H is the hopper, and B the reciprocating bar, whose reciprocation is governed by the holes connecting it with lever E. The bar rests on a series of guides, $a a$, which run on the bottom of the hopper, and, while giving ease of motion, prevent the breaking of

seed, which invariably work under the slide. The discharge-perforations $b b$ have an upward rim the height of the guides a , so that when the discharge is through but a portion of them the seed will not flow from those under the bar. The bar is notched, as seen at D, and each notch contains a series of pins, $c c$. The seed is thus certain to be well agitated over the discharge-openings, and, moreover, these openings can never be choked by impurities in the grain of large size, such as straw and other litter.

I claim—

The notches of the bar, with the series of pins c therein, in combination with the guides $a a$ and upward-projecting rims i of the discharge-openings b , substantially as set forth.

In testimony whereof I have hereunto set my hand before two witnesses.

M. D. WELLS.
